S. STEIN

JEWEL SETTING

Filed April 14, 1922

UNITED STATES PATENT OFFICE.

SOLOMON STEIN, OF WASHINGTON, DISTRICT OF COLUMBIA.

JEWEL SETTING.

Application filed April 14, 1922. Serial No. 552,441.

To all whom it may concern:

Be it known that I, SOLOMON STEIN, a citizen of the United States, residing at Washington, in the District of Columbia, have invented certain new and useful Improvements in Jewel Settings, of which the following is a specification, reference being had therein to the accompanying drawings.

10 This invention relates to jewel settings and mountings and has for an object to provide improved means for setting a stone in a mounting in such manner that it is held firmly and rigidly in position and permits the setting of stones of different sizes in the same mounting as occasion may require.

A further object of the invention is to provide a mounting having upon the inside a screw-threaded opening with an over-hang or shoulder at the upper and outer end with a screw-threaded sleeve of improved type insertible into the screw-threaded opening against the stone held by the over-hang and retaining such stone firmly in position.

A further object of the invention is to provide means for setting a stone in a mounting of any usual and ordinary type in such manner that as occasion may require 30 the stone may be removed from the mounting and replaced by a different stone but to be retained firmly and securely in position until so manually removed.

A further object of the invention is to provide a mounting for a stone which is furnished in predetermined sizes so that the same equipment both as to the mounting and the means for retaining the stone may be employed for stones differing and varying in 40 size.

With these and other objects in view the invention comprises certain novel parts, units, elements, constructions, combinations, arrangements and functions, as disclosed in 45 the drawing, together with mechanical equivalents thereof, as will be hereinafter more fully described and claimed.

In the drawings:

Figure 1 is a view of a conventional ring 50 in side elevation with a stone mounted therein according to the present invention;

Figure 2 is a sectional view through a ring showing the relation of the parts;

Figure 3 is a sectional view of a mounting 55 as it will be furnished prior to the en-

larging of the stone opening in the top of the mounting;

Figure 4 is a sectional view through the ring showing the mounting from the bottom with the stone in position; 60

Figure 5 is a top plan view of a mounting in accordance with the present invention shown in a brooch;

Figure 6 is a top plan view of a mounting in accordance with the present invention shown in a bracelet; 65

Figure 7 is a transverse sectional view through either of the mountings shown at Figures 5 or 6;

Figure 8 is a view in end elevation of 70 one of the sleeves indicating a thicker sleeve than that shown for instance at Figures 2 and 4, whereby a smaller stone is retainable in a threaded opening in a mounting of the same size; 75

Figure 9 is a view of the form in which the threaded sleeve will be furnished by the manufacturer in indeterminate length to be cut by the jeweler into required lengths for the work in hand; 80

Figure 10 is the internally screw-threaded sleeve used for the square setting as at Figure 11 into which the threaded sleeve shown at Figure 9 is inserted;

Figure 11 is a fragmentary detail sectional view of the under side of a mounting with a square opening with the two sleeves in position to hold a stone; and 85

Figure 12 is a view in side elevation of the sleeve to be inserted into the threaded 90 opening of the mounting shown at Figure 3.

Like characters of reference indicate corresponding parts throughout the several views. 95

It is well known that in the usual setting of stones in articles of jewelry, as for instance in a ring, an opening is provided for the stone and parts of the mounting are inset as claws engaging the edge of the stone for holding the stone in position. The setting of a stone in this manner is a delicate operation, as the claws must be forced inwardly exactly the right distance to properly clamp the stone, which results 105 many times in breaking the stone while setting. In the present case the mounting is provided with an opening from the under or reverse side into and through which the stone is inserted. At Figure 1 the stone 110

is of substantially the same size as the screw-threaded opening 11 in the ring 12 for mounting a gem or the like. At the top, however, an overhang or shoulder 13 is 5 provided against which the inclined sides or facets of the stone engage at the edge. A screw-threaded sleeve, shown as an entirety at 14, is inserted into the threaded opening 11 engaging the under side of the 10 stone, clamping it firmly against the overhang 13. The threaded sleeve 14 is preferably provided with some form of opening or recess, as the notch 15, for engaging a wrench or tool or spanner of some nature 15 for tightening the sleeve in position, and when in position a portion of the sleeve is swaged into a recess 16 in the mounting, preventing its return movement except when force is applied thereto for the purpose of withdrawing the sleeve. When set 20 in a ring the sleeve would be provided with a concave formation at the bottom, as indicated at 17, to conform to the curvature of the ring. When, however, the stone and 25 sleeve are set in a different form of ornamental ware, as the brooch 5 or the bracelet 6, the bottom may be perpendicular to its axis, as indicated at 18. The brooch or bracelet is provided with a similar overhang 30 19 engaging the stone 10 in the same manner.

It is the intent of the present invention to furnish the screw-threaded sleeve 14 in indeterminate length, as shown in Figure 9, in which case it is desirable to drill or 35 perforate the screw at intervals, as indicated at 20, so that when cut to the required length an instrument or point may be inserted in any of these perforations for the purpose of rotating the sleeve to clamp the stone in position.

At Figure 3 is shown the form of mounting furnished ordinarily by the manufacturer to the jeweler, the top 21 being ordinarily perforated only with a small opening 45 as shown at 22 which is reamed out by the jeweler to fit any size of stone required. As shown in dotted lines two sizes are suggested, it being obvious that variation of size is only limited by the size of the mounting; that is to say in case the stone to be 50 set in the mounting is not of such size as to completely fill the maximum opening 11, the opening as indicated at 22 is reamed out and tapered only sufficiently large to engage the edges of the stone in the manner hereinbefore mentioned, and a sleeve 23, as shown at Figure 8, thicker at the stone-engaging end than the sleeve indicated at Figures 2 and 12, will be employed so that it will engage the under 55 side of the stone and clamp it firmly in position in the same manner.

A certain type of mounting is now furnished to jewelers having what is known as a square opening, indicated at 24. This opening has its corners removed so that it is not

in fact square, but is so termed. To accommodate the type of setting in this type of mounting, a sleeve 25 is first inserted into this square opening and soldered therein. As shown at Figure 10 this sleeve, indicated 70 as 25', also is furnished in indeterminate lengths and cut as occasion may require, the internal screw threads in this sleeve fitting the external screw threads of the clamping sleeves furnished so that this clamping sleeve 75 26, as shown at Figure 11, will be identical with the other clamping sleeves, but instead of engaging directly the mounting as furnished, they will engage the intermediate sleeve 25, as shown at Figure 11.

At said Figure 11 a square in double dotted lines is shown. The inner dotted square is intended to represent the opening in the front of the mounting, while the outer square represents a square stone with its margins 80 engaging the margins of the opening. It will be obvious that the stone will be placed in such position with the sleeve 26 removed, which sleeve will thereafter be placed in position within the sleeve 25 clamping the stone 90 in position.

At Figure 2 the mounting 12 is shown as provided with side openings 27, such openings, however, being purely ornamental, but in that case the sleeve 14 after setting is 95 drilled with registering openings 28, simply to carry out the ornamental effect of the complete setting.

In any event, the back of the stone is at 100 all times visible through the sleeves 14, 18 or 23 to get any effect of light which may 105 be desired thereby, or for the purpose of examining the back of a stone when inspection is desired. It will be apparent that the mountings of various types, rings, or other articles of jewelry, may be and will be furnished the jewels unset, but with the openings in the back properly drilled and threaded to receive the threaded sleeve shown in indeterminate lengths, as shown at Figure 9. The mounting will be properly prepared to 110 receive the stone, as by reaming out the opening 22 shown in the ring at Figure 3 until the stone extends the desired distance above the top of the mounting with only the edge of the stone engaged by the overhang and the sleeve is then cut to the proper length and seated after which it is upset as indicated at Figure 115 4 merely for the purpose of preventing accidental displacement. In this manner stones of various sizes may be quickly and readily set in stone mountings without danger of breakage and without danger of loss of stone after setting.

What I claim to be new is:

A jewel mounting comprising a top composed of a relatively thin plate, having an opening in its centre proportioned and adapted to serve as a centering guide for a reamer to be applied from the under side to ream 120 130

out the opening with a taper the larger end of which is below, the smaller end being sufficiently smaller than the jewel to engage the periphery of the jewel and position it within 5 the taper, said mounting being provided also with an internally threaded bore larger than the larger end of the tapered portion and concentric therewith, and an externally threaded member fitted to the threaded bore 10 and provided at its upper end with a cen-

tral cavity, the end margin of which is proportioned and adapted to engage the under side of the jewel when the member is screwed home and maintain it rigidly within said taper with a portion extending through the 15 smaller end and exposed above the top.

In testimony whereof I hereunto affix my signature.

SOLOMON STEIN.
